(57) **CLAIM**

The ornamental design of an adult novelty, substantially as shown and described.

DESCRIPTION

FIG. 1 is a top view of the adult novelty, showing my new design;

FIG. 2 is bottom view of the adult novelty in FIG. 1;

FIG. 3 is a left view of the adult novelty in FIG. 1;

FIG. 4 is a right side view of the adult novelty in FIG. 1;

FIG. 5 is a front side view of the adult novelty in FIG. 1;

FIG. 6 is a back view of the adult novelty in FIG. 1;

FIG. 7 is a left perspective view of the adult novelty in FIG. 1; and,

FIG. 8 is a back perspective view of the adult novelty in FIG. 1.

The evenly spaced broken lines shown in the drawings are for the purposes of illustrating environmental structure, which form no part of the claimed design. The dash dot broken lines represents a boundary line, which form no part of the claimed design.

1 Claim, 8 Drawing Sheets
